UNITED STATES PATENT OFFICE.

WILLIAM W. FRY, OF LOS ANGELES, CALIFORNIA, ASSIGNOR OF ONE-HALF TO ROBIN-
SON PACKER COMPANY, OF TULSA, OKLAHOMA, A CORPORATION OF OKLAHOMA.

WELL CASING.

Application filed December 10, 1924. Serial No. 754,991.

This invention relates to a method of casing drill wells and is especially adapted to be used for casing oil wells, the object being to provide a method by means of which the well 5 can be cased by one connected string of different sized casings so connected together that they can be readily placed in position within the well and removed therefrom so that in case of a dry hole, the lower or smaller 10 string can be first removed and the next succeeding strings of casings of different sizes removed.

Another and further object of my invention is to provide a method for casing wells, 15 wherein the water and gas are shut off from between the different sized casings, by packers arranged between one set of casings and the next succeeding casing on the inside, thereby enabling the operator to cut off the 20 water and gas, without the use of what is known as an outside packer, shoe, or other device, the setting of which has to depend upon the earth formation.

A still further object of my invention is to 25 provide a method of casing wells which is considerably cheaper than the prior methods now in use as the various strings of casings running from the top of the hole down are eliminated and one connected string is employed.

Another and further object of the invention is to provide a method of casing wells which allows the casings to be handled by a 30 lighter drilling machine as the casing can be formed lighter and it is not necessary to support the enormous weight as is now the case where the strings extend from the surface downwardly.

Other and further objects and advantages 35 of the invention will be hereinafter set forth and the novel features thereof defined by the appended claim.

In the drawings,

Figure 1 is a vertical section through a 40 casing in position within the well showing the method of casing a well in accordance with my invention;

Figure 2 is a similar view showing a well 45 cased by the ordinary method now in use; 50 Figure 3 is a detail section showing a packer arranged between the ends of the connected sections and a fishing tool for removing the sections.

In carrying out my method I have illus- 55 trated a well having a depth of 4000 feet

cased with a series of strings of various lengths and sizes comprising an upper string of 500 feet of 15½ inch pipe, a second string of 500 feet of 12½ inch pipe, a third string of 1000 feet of 10 inch pipe, a fourth string of 1000 feet of 8¼ inch pipe and a fifth string of 1000 feet of 6½ inch pipe, these strings being lowered into the hole as the well is drilled, the upper ends being connected together by a specially constructed packer. 60 65

These packers are provided with heads which are adapted to be engaged by a fishing tool.

In the drawing I have shown a well having a depth of 4000 feet cased by sections 1, 2, 3, 4 and 5, one string telescoping within the other string and having packers 6 arranged as clearly shown so as to completely cut off the water and gas. 70

To encase a well having a depth of 4000 feet under my improved method approximately 4000 feet of piping is used, while with the general method now in use of casing a well as shown in Figure 2, approximately 10,500 feet of piping is used, as each string 80 extends from the surface downwardly, while with my improved method I employ a series of connected strings. 75

This enables a well to be cased very much cheaper than with the method now in use, and also dispenses with approximately 7,000 feet of casing, and as one continuous connected string is used in my method, a well drilling apparatus of lighter construction can be used to place, move, and replace the casing in position, as the operator shall determine in the drilling of the well, and to remove the same, the packing feature enabling the sections to be placed one within another, at any desired point, changed, or held in that position, without the use of outside packers, shoes, or other devices against the earth formation of the well. 85 90 95

A fishing tool 7 is employed in setting, changing location of and removing the 100 strings and is adapted to be tripped by allowing the same to engage the bottom of the hole and when raised engages the head of the packer in such a manner that a specially constructed packer forms a support for the string so 105 the strings from the bottom upwardly can be removed one at a time in case it is desired to dismantle the well.

In carrying out my method the first 500 feet of the casing is preferably let down and 110

screwed one joint at a time together until the five hundred feet level has been reached and the next string of casing can be set in all at one time as the drilling continues and so on 5 down until the bottom of the well is reached, the strings being connected by the improved construction of packer so that the water and gas is kept out of the well from the next outside string as the well is drilled from the inside 10 side by the packer arranged between the sections, thereby overcoming the difficulties now existing of having to pack the well against the earth formation to accomplish that end.

While in the drawing I have shown a casing 15 composed of a plurality of telescoping sections of various sizes, it is, of course, understood that by having specially constructed packers, any string can be eliminated as for example, the 8 $\frac{1}{4}$ inch string could be eliminated and the lower string of 6 $\frac{5}{8}$ inch pipe 20 be formed 2000 feet in length instead of 1000 feet.

My improved method of casing wells does not interfere with the use of outside packers, 25 shoes or other devices, if desired so as to pack the casing at any desired point against the wall of the well to hold back pressures on the lower strings, etc., but enables a well to be drilled so that it is under the control of the operator at all times as the strings can be set 30 one within the other at any desired point and the water and gas completely shut off by an inside packer arranged between the telescoping strings.

35 The method of now casing wells is clearly shown in Figure 2 of the drawing and it will be noted that each string extends from the surface downwardly, thereby necessitating the use of approximately 6000 more feet 40 of pipe to case the well than with the method as clearly defined in this invention and as the smaller string extends from the surface to the bottom of the hole, it necessitates the use of a heavy drilling machine.

45 By casing the well under my improved method, the well can be drilled to a greater depth with a light drilling machine and it is only necessary to handle a 1000 feet of casing at one time and it is, of course, understood that if desired, these strings can be 50 shortened or lengthened.

The drill well encased under my improved method not only has the above advantages, but many others, especially the advantage

of overcoming the great pressure when a 55 gusher is struck in drilling the well as with my improved method this pressure only has to pass through a short string of a certain size piping before it is relieved by reaching a larger string and as the pressure continues 60 upwardly, it is gradually relieved while with the old method the inside casing extends from the bottom of the hole to the top and the pressure cannot be relieved until it reaches the top. 65

From the foregoing description it will be seen that I have provided a method of casing a drill well in which the casing of the well is under the control of the operator at all times rather than under the control of the earth 70 formation as is the case in drill wells of this nature as now carried out, as the water and gas are shut off by packing between one set of casing and the adjacent set.

While in the drawing and specification I 75 have only shown and described broadly a casing for a drill well, it is, of course, understood that the strings of casings will have to be connected together by a packer of particular construction in order to allow the casing 80 to be lowered and set at any desired position and to facilitate the changing and removing of the strings of casings by a finishing tool.

It is, of course, also understood that the usual piping for drawing the oil from the 85 well drilled is used in connection with the casing.

Of course, I am aware that the casing constituting the different strings can be formed of sections either welded together or coupled 90 together by the usual coupling sleeves now in use and therefore I do not wish to limit myself to the particular manner of connecting these sections together to form the strings. 95

What I claim is:—
A casing for wells composed of a series of telescopic strings extending from the top to the bottom thereof having packers arranged between the concentric walls of the overlapping strings at their upper ends for detachably connecting said sections together, said packers having head portions extending inwardly beyond the inner walls of the overlapping strings.

In testimony whereof I hereunto affix my 10 signature.

WILLIAM W. FRY.
